UNITED STATES PATENT OFFICE.

WILLIAM A. WILKINSON, OF MINNEAPOLIS, MINNESOTA.

LOG STOPPING AND HOLDING MECHANISM FOR SAWMILLS.

932,217.

Specification of Letters Patent.

Patented Aug. 24, 1909.

Application filed February 23, 1909. Serial No. 479,537.

To all whom it may concern:

Be it known that I, WILLIAM A. WILKINSON, a citizen of the United States, residing at Minneapolis, in the county of Hennepin 5 and State of Minnesota, have invented certain new and useful Improvements in Log Stopping and Holding Mechanisms for Sawmills; and I do hereby declare the following to be a full, clear, and exact description of the 10 invention, such as will enable others skilled in the art to which it appertains to make and use the same.

My invention has for its object to improve the construction of that type of saw mill machinery used for cutting logs into different lengths or into different numbers of sections, and is directed particularly to the provision of improved means for stopping and holding the log while it is being sawed off.

20 To the above ends, the invention consists of the novel devices and combinations of devices hereinafter described and defined in the claims.

In machines of the class above indicated, 25 the logs are fed to the saw over a sluice or channel shaped skid by an endless feed chain, and hitherto, it has been necessary to stop the feed chain as well as the log while the log is being sawed. The momentum of the 30 feed chain and the heavy mechanism employed to drive the same is very considerable, and hence, it has been difficult to stop the log, with any degree of accuracy, at the point where it is desired to saw the log, and 35 furthermore, there has been a loss of time in bringing the log, the feed chain and the chain driving mechanism to a standstill. Furthermore, the waste of lumber due to inaccurate sawing of the logs, is a very serious 40 matter.

My invention provides means whereby the feed chain is permitted to continuously run, and the log is forced from the chain and held in a position in which it may be sawed without 45 causing the saw to engage the chain. This radical departure in the manner of handling logs enables the log to be very quickly and accurately brought to a standstill and held for sawing. When the log has 50 been sawed in two at its intermediate portion, or when an end has been sawed therefrom, it may be dropped back onto the feed chain and fed onward thereby without at any time interrupting the movement of the 55 feed chain.

In the accompanying drawings which

illustrate the invention, like characters indicate like parts throughout the several views.

Referring to the drawings: Figure 1 is a transverse vertical section with some parts shown in diagram only, and with some parts broken away, illustrating my invention; Fig. 2 is a fragmentary view in section, showing on a larger scale than in Fig. 1, certain of the parts shown in the said latter view; Fig. 60 3 is a plan view with parts broken away and parts removed, illustrating a slightly modified construction; and Fig. 4 is a transverse vertical section taken on the line $x^4 x^4$ of Fig. 3. 65

The numeral 1 indicates a skeleton timber frame work which supports the log guiding sluice or skid 2 and inclined decks 3.

The numeral 4 indicates portions of the 70 endless feed chain, which as shown, is arranged to run over a metal guide channel 5 secured in the bottom of the sluice 2. The feed chain may be of any suitable construction, and any suitable chain driving mechanism which will impart continuous movement 75 to the chain may be employed.

A saw 6, as is customary, is mounted upon a pivoted swinging beam 7, and is driven in the customary way by a belt and pulley driving mechanism indicated as an entirety by 80 the numeral 8. Also, as is customary, the saw is moved to and from its operative position by a small cylinder and piston engine 9, the stem 10 of which is connected to the saw supporting beam 7. 85

In Figs. 1, 2 and 4, logs are indicated by 90 the numeral 11, and in Fig. 2, logs of different diameter are indicated by full and dotted lines.

In applying my invention, I provide at 95 one side of the sluice 2, a multiplicity of log engaging abutments or stops, and on the other side of said sluice, I provide a multiplicity of so called log engaging push bars, and by means of the latter, the log may be 100 pushed or rolled onto one side of the sluice against the said abutments and there held in position for sawing entirely out of reach of the feed chain 4.

In the construction illustrated in Figs. 1 105 and 2, end and intermediate abutments are afforded by heavy, short posts 12, rigidly secured to the frame work 1, and provided on their inner sides with metal facing strips 13 having log engaging teeth or barbs 14 for 110 engagement with logs of different diameter, as best indicated in Fig. 2.

In the construction illustrated in Figs. 3 and 4, the end abutments are the same as in Figs. 1 and 2, but the intermediate abutment is in the form of a metal plate 15 pivoted at 16 and provided with log engaging teeth 17. This movable abutment 15 is preferably arranged to be operated, at will, by a small cylinder and piston engine 18, the long stem 19 of which is connected thereto. 5

10 This movable abutment is adapted to be moved toward and from the log and is therefore especially well adapted for action on a crooked log, which would not aline with three fixed stops. Also in Fig. 3, an additional fixed intermediate stop or abutment 15 is indicated, and the saw 6 is arranged to cut the log at a point between this post and the movable abutment 15.

15 In all the drawings, the so called push bars 21 of which, as shown, there are three, are connected to arms 22 of a rock shaft 23 mounted in suitable fixed bearings on one side of the frame work 1. The upper ends of the push bars 21 are preferably formed 20 with teeth 24, and they are held in alinement with the end and intermediate abutments and are supported by suitable guides formed in the adjacent side of the log guiding sluice 2. The push bars 21 are operated, at will, 25 by a cylinder and piston engine 25, the stem 26 of which, as shown, is connected to a suitably guided cross head 27 (see Fig. 4), which in turn, is connected by a rod 28 to an arm 29 of the rock shaft 23.

30 35 When a log is to be stopped and held for sawing, the push bars 21, by means of the engine 25, are thrust endwise against the log and are caused to force the log upward on one side of the sluice 2 out of reach of the 35 chain 4, and against the coöperating end abutments and fixed or movable intermediate abutment, as the case may be, and the log thus handled, will be quickly brought to a standstill and will be firmly held by the coöperating abutments and push bars. The 40 teeth on the abutments and the push bars very greatly assist in bringing the log to a quick standstill and firmly holding the same, and as best shown in Fig. 2, these teeth, 45 are so arranged that they will engage properly, with logs that vary a great deal in diameter. When the movable intermediate abutment is employed, it will usually be forced against the log after the log has been 50 forced against the fixed end abutments, but before the saw is moved into action on the log.

55 In some instances, it may be necessary or desirable to make provision for stopping the log feeding chain or other log feeding means, to prevent logs that are fed close together, from bumping into a log while it is being held and sawed. Even in this arrangement, however, the log will be forced from the feeding 60 means and will be stopped independently

of the stopping of the feeding chain, and the latter will be brought to a standstill at any desired time subsequent to the removal of the log to be sawed therefrom.

What I claim is:

70 1. In a machine of the kind described, the combination with a saw and means for feeding the logs past said saw in a direction transversely thereof, means for forcing the logs laterally out of reach of said feeding means and for holding the same in a fixed position while being sawed.

75 2. In a machine of the kind described, the combination with a saw and means for feeding the logs past said saw, transversely thereof, of log holding abutments on one side of said feeding means, and means for forcing the log laterally out of reach of said feeding means against said abutments and coöperating with said abutments to hold the log in a fixed position while being sawed.

80 3. In a machine of the kind described, the combination with a saw and means for feeding the logs past the saw, of abutments at one side of said feeding means, and push bars at the other side of said feeding means, 85 operative to force the log laterally out of the reach of said feeding means, against said abutments, and coöperating with said abutments to hold the logs in a fixed position 90 while they are being sawed.

95 4. In a machine of the kind described, the combination with a saw, a log guiding sluice and a log feeding chain, of fixed abutments at the saw side of said sluice, push bars 100 mounted for endwise movements at the other side of said sluice, and power actuated means for simultaneously moving said push bars against the log, said push bars serving to force the log laterally out of 105 reach of said feed chain, against said abutments, and coöperating with said abutments to hold said log in a fixed position while it is being sawed.

110 5. In a machine of the kind described, the combination with a saw, a log guiding sluice and a log feeding chain, of toothed abutments at one side of said sluice, toothed push bars mounted for endwise movements at the other side of said sluice, a rock shaft 115 having arms connected to said push bars, and a cylinder and piston engine with connections to said rock shaft for moving said push bars simultaneously against the log, thereby causing said push bars to move the log laterally out of reach of said feed chain, and into position for coöperation with said toothed abutments for holding the log in a 120 fixed position while it is being sawed.

125 6. In a machine of the kind described, the combination with a saw, a log guiding sluice and a log feeding chain, of fixed and movable abutments at one side of said sluice, push bars mounted for endwise movements at the other side of said sluice, and power 130

actuated means for simultaneously moving said push bars against the log, said push bars serving to force the log laterally out of reach of said feed chain, and coöperating with said abutments to hold the log in a fixed position while it is being sawed.

7. In a machine of the kind described, the combination with a saw and means for feeding the logs past said saw, of an engine actuated movable abutment at one side of said log feeding means, and an engine actuated push bar at the other side of said log feeding

means operative to move the log laterally against said abutment, and coöperating therewith to hold the log in a fixed position 15 for sawing, out of the reach of said log feeding means.

In testimony whereof I affix my signature in presence of two witnesses.

WILLIAM A. WILKINSON.
